US0D1080119S

(12) **United States Design Patent** (10) **Patent No.:** **US D1,080,119 S**
Xiao (45) **Date of Patent:** **** Jun. 17, 2025**

(54) **TRASH CAN LOCK STRAP**

(71) Applicant: **Shenzhen Jinfeng Haotian E-commerce Co., Ltd.**, Guangdong (CN)

(72) Inventor: **Feng Xiao**, Guangdong (CN)

(73) Assignee: **Shenzhen Jinfeng Haotian E-commerce Co., Ltd.**, Guangdong (CN)

(**) Term: **15 Years**

(21) Appl. No.: **29/973,366**

(22) Filed: **Nov. 15, 2024**

(51) LOC (15) Cl. **09-09**

(52) U.S. Cl. **D34/10**

(58) **Field of Classification Search**

USPC D8/44, 72, 367, 394; D9/435; D34/10, D34/11
